STITCHLESS WALLET CONSTRUCTION

Francis A. Brady, Canandaigua, N. Y., assignor to
Hickok Manufacturing Company, Inc., Rochester,
N. Y., a corporation of New York

Application July 29, 1949, Serial No. 107,600

3 Claims. (Cl. 150—38)

1

The invention relates to a stitchless wallet construction.

An object of the present invention is to provide a simple, strong, durable and highly attractive stitchless wallet of practical, inexpensive construction, comprising an outer wall having pocket forming members and a separate inner wall confined in position by flaps of said members and cooperating therewith to form pockets at the outer face of the inner wall, one of the pockets being equipped with a removable card case positively secured in position with respect to such pocket forming member by fastening means carried by one of the covers of the card case and the wallet.

A further object of the invention is to provide a stitchless wallet comprising an outer wall having pocket forming members and a separate inner wall confined in position within the wallet by flaps of said members and cooperating therewith to form pockets, one of the pockets being provided with a removable card case and the other pocket being provided with an insert cooperating with such pocket forming member to provide additional pockets.

A further object of the invention is to provide a stitchless wallet comprising an outer wall having pocket forming members and a separate inner wall positively interlocked with the pocket forming members which are also positively interlocked with the outer wall by means of end flaps of the outer wall having tongues extending through slits in the pocket forming members and interlocking the end flaps with the end portions of the pocket forming members.

Another object of the invention is to provide a stitchless wallet having inner and outer walls and provided with a dividing strip retained in position and concealed at the upper portion by top marginal flaps of the outer wall of the wallet to form a concealed compartment especially adapted for holding bills of high denominations, checks, and other papers, so that when the wallet is opened only a second bill holding compartment designed for holding bills of small denomination is disclosed to view, said dividing strip being cut away at its upper corners to afford ready access to the contents of the concealed compartment to facilitate easy removal of bills or the like.

With the above and other objects in view, the invention consists in the construction and novel combination and arrangement of parts herein-after fully described, illustrated in the accompanying drawings and pointed out in the claims hereto appended, it being understood that vari-

ous changes in the form, proportions, and minor details of construction, within the scope of the claims, may be resorted to without departing from the spirit or sacrificing any of the advantages of the invention.

In the drawings:

Fig. 1 is an elevation of a stitchless wallet constructed in accordance with this invention and shown in open position;

10 Fig. 2 is a longitudinal sectional view on the line 2—2 of Fig. 1;

Fig. 3 is a longitudinal sectional view on the line 3—3 of Fig. 2;

15 Fig. 4 is a transverse sectional view on the line 4—4 of Fig. 1;

Fig. 5 is a transverse sectional view on the line 5—5 of Fig. 1;

20 Fig. 6 is a plan view of the blank from which the outer wall, the pocket forming members and the flaps and tabs are formed;

Fig. 7 is a plan view of the inner wall;

Fig. 8 is a plan view of the dividing strip;

Fig. 9 is a plan view of one of the reinforcements of the pocket forming members;

25 Fig. 10 is a plan view of one of the reinforcements of the flaps of the pocket forming members;

Fig. 11 is a detailed perspective view of the card case, partially open to show the front and back of the cover and the intermediate leaves;

30 Fig. 12 is the blank from which the pocket insert is formed;

Fig. 13 is a detail perspective view of the pocket insert, partly open to show the front and rear sides thereof;

35 Fig. 14 is a detail view of one of the transparent leaves of the card case.

In the accompanying drawings, in which is illustrated the preferred form of the invention,

40 1 designates an oblong outer wallet wall constructed of leather or other suitable flexible sheet material and provided at the bottom with pocket-forming members 2 and 3 extending upwardly in parallelism with the outer wall and provided at the top with flaps 4 and 5 which fold downwardly and inwardly within the wallet over an oblong inner wall 6.

45 The flaps are preferably tapered slightly by arranging their edges 7 and 8 divergently at an inclination, and the outer ends of the flaps 4 and 5 are provided with parallel slits 9 forming tongues 10, located at a point spaced from the upper and lower edges of the flaps 4 and 5 and extending longitudinally of the wallet through vertical 55 transverse slots 11 formed in the end portions

of the inner wall 6 whereby the inner wall which is confined in cooperative relation with the pocket forming members by the flaps 4 and 5 is positively interlocked with the flaps.

The pocket forming members and the flaps are provided with reinforcements 12 and 13 each consisting of a sheet of flexible material. The reinforcements are adhesively secured to the inner faces of the pocket forming members and the flaps thereof, and the reinforcements 13 of the flaps are provided with parallel slits 14 corresponding with the tongue forming slits 9 and forming tongue portions 15 which reinforce the tongues 10 of the flaps. The portions of the flaps above and below the tongues 10 with the corresponding portions of the reinforcements of the flaps are folded around the end portions of the inner wall and adhesively secured to the same.

The pocket forming members 2 and 3 cooperate with the inner wall to provide at the outer face of the inner wall exterior pockets open at their inner ends and having their outer ends closed by end flaps 16 and 17 which are foldable inwardly over the outer ends of the pocket forming members and are provided with longitudinal dovetail tongues 18 and 19 having their ends cut at an angle to form inwardly converging end edges 20 and 21. The tongues 18 and 19 taper inwardly and are passed through vertical slits 22 and 23 and as the tongues 18 and 19 are of a length greater than the length of the slits 22 and 23, the angularly cut end edges 20 and 21 project beyond the ends of the slits and positively interlock the tongues 18 and 19 in the slits 22 and 23. The tongues 18 and 19, after being passed through the slits 22 and 23, extend outwardly with respect to the slits and are located wholly within the contour of the narrow marginal end flaps 16 and 17 which extend upwardly from the lower edge of the outer wall to the upper edge of the inner wall. The slits 22 and 23 are arranged closely adjacent the outer side edges of the pocket forming members and when the end flaps are folded over the outer side edges of the pocket forming members, they extend only to the slits and they provide a narrow edging at the ends of the wallet extending from the lower edge of the outer wall to the upper edge of the inner wall.

The end flaps 16 and 17 and the tongues 18 and 19 are adhesively secured to the contiguous portions of the wallet. The wallet is folded transversely in the conventional manner and when folded the pockets formed by the pocket forming members and the inner wall are arranged within the wallet. The outer wall is provided at the bottom at the center with a flap 24 which is folded inwardly against the inner face of the outer wall and is adhesively secured to the same to reinforce the central portion of the lower edge of the outer wall at the space between the open inner ends of the pockets.

The pocket formed by the pocket forming member 2 and the inner wall 6 receives a removable card case 25 consisting of a cover 26 and a plurality of leaves 27 arranged between the outer and inner sides 28 and 29 of the cover. The cover preferably consists of an oblong sheet of leather or other suitable flexible material which is folded transversely to form the outer and inner sides 28 and 29. The leaves 27, which may be constructed of any suitable material, preferably consist of sheets of Celluloid or similar transparent material, and are provided at their inner vertical edges with strips 30 of fabric or other suitable material which are adhesively or other-

wise secured to the leaves and to the cover of the card case. The leaves 27 and the inner side 29 of the cover are inserted in the card case receiving pocket and the outer cover is provided with a snap fastener part 31 which detachably engages a snap fastener part 32 mounted on the adjacent end flap 16 of the outer wall, whereby the card case is securely retained in the card case receiving pocket. The outer cover portion of the card case is oblong and is of sufficient dimensions to substantially cover the pocket forming member over which it lies and substantially conceals the same when the card case is arranged within the card case receiving pocket and the outer cover portion of the card case is closed. Instead of a snap fastener, any other suitable fastening means may be employed for securing the outer side of the cover to the end flap 16.

The end member 3 is provided with a slit 33 extending from the lower portion of the end member to the upper portion thereof and terminating short of the top and bottom of the same and removably receiving an insert 34 consisting of a substantially oblong sheet of leather or other suitable flexible material folded transversely in its center to form two sides 35. The side portions of the insert forming sheet are arranged at a slight angle to each other, as clearly illustrated in Fig. 12 of the drawings. The insert 34 extends through the slit 33 of the pocket forming member 3 and it projects exteriorly beyond the slit and provides additional pockets, and it is reversible to form a further additional pocket. Also when the insert is arranged in its normal position, as shown in Fig. 1 of the drawings, the two sides of the insert provide an interior concealed pocket and access may be had to the same by removing the insert from the slit.

The inner wall 6 is provided at its upper and lower edges with central extensions 36 and 37; the upper extension is folded flat against the inner face of the inner wall and provides a reinforcement at the central portion where it is usually grasped to open the wallet to afford access to the bill receiving compartments, herein-after described and located between the inner and outer walls of the wallet. The extension 37 at the bottom of the inner wall is folded on itself and provides a central downwardly projecting portion 38 which extends below the lower edges of the end portions of the inner wall, but the bottom extension may be folded completely against the inner face of the end wall in the same manner as the top extension so that the lower edge of the inner wall will be straight or continuous like its upper edge.

Within the wallet between the inner and outer walls is arranged a dividing strip 39 consisting of an oblong sheet of flexible material having its upper marginal portion 40 bent or folded downwardly and adhesively secured to the rear face of the dividing strip to reinforce the same. The upper corners of the dividing strip are cut away at 41 and the central portion of the lower edge is recessed or cut away at 42 to span the bottom central tab 24 of the outer wall. The lower corners of the dividing strip are also cut away at 43 and the lower edge portion 44 at opposite sides of the central cut away portion 42 is adhesively secured to the inner and outer walls at the lower edge portions thereof.

The dividing strip divides the space between the inner and outer walls into two bill receiving compartments and the compartment between the dividing strip and the outer wall constitutes

a secret bill compartment as the upper edge of the dividing strip is engaged and concealed by upper flaps 45 formed by an upper marginal extension of the outer wall. The upper marginal extension is cut away at its center to form the two top flaps 45 and is folded downwardly and inwardly within the wallet and is slit at 46 at the outer ends of the flaps to provide tabs 47 which are folded downwardly and inwardly and adhesively secured to the inner face of the outer wall. The slits 46 do not extend the entire width of the flaps 45 which thereby have their upper portions connected with the tabs 47 and are retained in position within the wallet by said tabs as the portions connecting the flaps 45 with the tabs 47 resist any tendency of the flaps 45 to move away from a position contiguous to the outer wall. When the wallet is opened and the inner and outer walls spread, only the bill receiving compartment which is located between the dividing strip and the inner wall will be exposed as the upper portion of the dividing strip will be concealed behind the downwardly folded top flaps 45 of the outer wall. The cut away portions 41 at the upper corners of the dividing strip expose the corner portions of bills contained within the secret compartment and facilitate ready removal of bills or other papers from such compartment when the flaps 45 are raised to expose the contents of the secret compartment.

I claim:

1. A stitchless wallet comprising an outer wall, an inner wall extending from one end of the wallet to the other, pocket forming members connected with and extending upwardly from the lower edge of the outer wall to the upper edge of the inner wall and arranged exteriorly thereof to form pockets exteriorly of said inner wall, said pocket forming members being provided with flaps folded over the upper edge of the inner wall and extending downwardly at the inner face thereof and confining the inner wall in the wallet and securing the pocket forming members to the inner wall, said pocket forming members each being provided adjacent its outer side edge with a straight marginal slit, narrow marginal end flaps connected with and extending from the end portions of the outer wall and folded over the side edges of the pocket forming members and having tongues extending through the marginal slits in the pocket forming members and securing the end flaps to said members, the flaps of the pocket forming members and the end flaps of the outer wall cooperating to hold the inner wall in a fixed position against movement longitudinally and vertically, and a card case extending into one of the pockets formed by the pocket forming members and having an outer cover portion overlying the contiguous pocket forming member and concealing the same, and a two-part fastener having one part mounted on the outer cover portion of the

card case and the other part on the marginal end flap, the two parts of the fastener being engageable with each other and retaining the card case within the card case receiving pocket and the outer cover portion closed and in position for concealing the underlying pocket forming member.

2. In a stitchless wallet comprising inner and outer walls, the outer wall being provided at its upper edge at its inner face with a narrow downwardly extending longitudinal flap and with top end tongues rigidly secured in face-to-face relation with the inner face of the outer wall and integrally connected with the top marginal flap adjacent to the upper edge of the outer wall and resisting the opening of the top flap, and a dividing strip consisting of an oblong sheet of flexible material arranged within the wallet between the said outer wall and the top flap and cut away at its upper corners at said top tongues and forming a concealed pocket, and said dividing strip being connected at its lower edge portion to the lower edge portion of the front wall.

3. In a stitchless wallet comprising inner and outer walls, the outer wall being provided at its upper edge at its inner face with a narrow downwardly extending longitudinal flap and with top end tongues rigidly secured in face-to-face relation with the inner face of the outer wall and integrally connected with the top marginal flap adjacent to the upper edge of the outer wall and resisting the opening of the top flap, and a dividing strip consisting of an oblong sheet of flexible material arranged within the wallet between the said outer wall and the top flap and cut away at its upper corners at said top tongues and forming a concealed pocket, said dividing strip being also cut away at its lower corners and provided at its lower edge portion with spaced extensions secured to the inner and outer walls of the wallet.

FRANCIS A. BRADY.
